PILOT DIRECTOR

Samuel M. Burka, Dayton, Ohio

Application November 13, 1934, Serial No. 752,900

6 Claims. (Cl. 33—204)

(Granted under the act of March 3, 1883, as
amended April 30, 1928; 370 O. G. 757)

The invention described herein may be manufactured and used by or for the Government for governmental purposes, without the payment to me of any royalty thereon.

5 It is an object of my invention to supply a device of extreme simplicity whereby the course of an aircraft may be readily directed by a navigator remotely located from the pilot flying said aircraft.

10 With the foregoing and other objects in view, which will appear as the description proceeds, the invention consists of certain new and novel improvements in pilot directors, which will be hereinafter more fully illustrated and described in the 15 accompanying drawing and more particularly pointed out in the appended claims.

Referring to the drawing, in which numerals of like character designate similar parts throughout the several claims:

20 In Fig. 1, the indicating portion of my device is shown as viewed by the pilot.

Fig. 2 is a plan view of the entire device, with foreshortened drive cable.

Fig. 3 is a sectional view taken on the line 3—3 25 of Fig. 2.

Fig. 4 shows an enlarged view of the window of Fig. 1.

Fig. 5 shows a similar view, with readings altered.

30 The indicating portion of my device is enclosed in a housing 1, provided with a small observation opening in the form of a window 2. Through the lower half of the window 2 is observed a limited portion of a cylindrical card 3. Graduations 4, 35 of varying depths, extend downwardly from the upper edge of the card 3. Vertically staggered numerals 5 are placed immediately beneath the 40 graduations 4. I have arbitrarily made the width of the window 2 such that at least seven of a card total of 72 equal graduations of arc are exposed to view at any one time. Since each graduation represents five degrees of arc, I have provided for 360° azimuth correction by means of twelve recurring sets or groups of six graduations and six figures

45 each, the figures being correspondingly arranged in each group. Through the upper half of the window 2 is observed a limited portion of a second cylindrical card 6. To avoid confusion, the aforesaid card is later termed a "reference" card.

50 A single graduation 7 extends upwardly from the lower edge of the card 6. As viewed in Fig. 1, the graduation 7 has been positioned midway between the left and right hand sides of the window 2. The card 6 is provided with twelve such graduations 7, each of which mark off 30° of arc. It,

therefore, may be properly assumed that the eleven recurring sets or groups of graduations stamped upon the card 3, which in Fig. 1 are hidden from view by the housing 1, have immediately opposite their numeral 3 eleven similarly hidden graduations 7 stamped upon the card 6.

I have arbitrarily made the window 2 such that, with the single exception of a small angular adjustment of the card 6, only one graduation 7 will appear at any one time. In the above referred to exception, before the disappearance of one graduation 7 behind a right or a left hand side of the window 2 there appears a previously hidden graduation 7 at a correspondingly opposite left or right hand side of the window 2.

In Fig. 2, the housing 1 is provided with a cover 8 (shown at the bottom of the figure) and an internal boss 9. The boss 9 is tapped with conventional pipe thread. An external projection at the rear of the housing 1 is provided with threads for receiving a nut 10 of a flexible drive cable 11. The uppermost portion of the drive cable 11 is secured to a control unit 12 by means of a nut 13. The control unit 12 consists of a housing 14, hand knob 15, gear 16 and worm 17.

In Fig. 3, I have selected as a mounting base for the card 3 of Fig. 1 a directional gyroscope 18. Obviously I might equally well have selected the card supporting element of a magnetic compass or other device which maintains a fixed direction in azimuth. The card 3 is secured to the gyroscope 18 by means of arms 19. A hollow boss 20 is provided at its lower extremity with a screen 21, and at its upper extremity with a suitable shoulder for receiving a ball bearing 22, held in place by a threaded collar 23. The bearing 22 secures the lower portion of the gyroscope 18 to the housing 1, while the upper portion thereof is pivoted about the bearing pin 24. The gyroscope 18 is energized by air evacuation from the housing 1, through the outlet provided by the boss 9. Those skilled in the art are well versed in the part arrangement and operation of directional gyroscopes.

The essence of my invention is contained in the 45 "reference card" 6. Briefly stated this card represents a plurality of laterally adjustable rubber lines, only one of which is generally visible through the window 2, as stated above. The reference card 6 is fixed to a gear 25 by means 50 of rivets 26. The gear 25 is in turn journaled to a boss 27 provided at the upper extremity of the housing 1. A worm 28 is journaled in bosses 29 and 30 provided in the under top surface of the housing 1. Through high and low pitch se- 55

lection, with reference to gears 17 and 25, a considerable number of turns of the knob 15 is made to effect less than one turn of the reference card 6. A check nut 31 is used to lock the bearing pin 5 24 against rotation with respect to the housing 1.

The operation of my device is as follows. Let it be assumed that a pilot has sighted a bombing objective and has brought the nose of his aircraft to bear thereupon. Unless he is fortunate 10 enough to be directly upwind or downwind of the aforesaid object, his aircraft will drift to right or left of a straight line drawn through the intersection of his perpendicular with the ground at any given moment and from thence 15 to the approximate center of the object he seeks to destroy. Having assumed the aforesaid heading, the pilot thereupon glances through the window 2 and observes the card arrangement of Fig. 4. He makes mental note that the graduation 20 1 of the reference card 6 is approximately midway between the numerals 2 and 3 of the graduations 4 stamped upon the card 3. As long as the navigator, in this instance the bomber, permits the reference card 6 to remain stationary 25 with respect to the housing 1 and the pilot so directs his aircraft that the numerals 2 and 3 remain positioned as shown in Fig. 4, the pilot is holding his aircraft's heading at zero azimuth deviation. If the pilot continues to maintain 30 the aforesaid heading he will discover, in a short period of time, that the nose of his aircraft is slowly drifting to right or left of his bombing objective. It is with correction of the aforementioned drifting that the following is concerned. 35

Simultaneously with the bringing, by the pilot, of the nose of an aircraft into preliminary alignment with an object to be bombed, the bomber assumes control of the aircraft's course. 40 Through employment of well known sighting means, he determines the course to be followed. He retains the pilot upon the same through continuous manipulation of the knob 15. One of the typical series of corrections incident to the above 45 may be observed by reference to Fig. 5, in which the bomber has moved the graduation 1 of the reference card 6 to the right of the position shown in Fig. 4. The pilot merely follows movement of the reference card 6 by identical and coinciding movement of the card 3, through use 50 of the rudder controls of his aircraft. It should be noted that the above heading correction is entirely devoid of involved mental process. The pilot has only to maintain the card graduations 55 in matched relationship. As has been previously stated, the interrelationships of the eleven hidden graduated sets and eleven hidden graduations 1 coincident therewith are identical to the matched relationship of the twelfth exposed set and graduation 1. As each exposed set and graduation 1 disappear behind the right or left hand side of the window 2, the pilot's eye automatically picks up an oncoming set and graduation 1 from the opposite left or right hand side 60 of the window 2. The bomber may, if necessity arises, accomplish a 360° correction from any original heading selected by the pilot. This broad range of correction finds particular application to large transport aircraft of all types. 65

70 I claim:

1. In a pilot director for aircraft, the combination with a device adapted to maintain a fixed direction in azimuth, of a housing for mounting said azimuth maintaining device, a card fixed to 75 said device having a plurality of equally spaced

graduations each provided with an identifying character such that the whole forms a series of groups of correspondingly arranged characters, a reference card rotatably secured to said housing coaxial with but not touching said azimuth card 5 and having equally spaced graduations identical in number to said recurring group of characters, and means for rotatably adjusting said reference card with respect to said housing, there being a window in said housing of sufficient size for viewing predetermined portions of said reference and azimuth cards. 10

2. In a pilot director for aircraft, the combination with a device adapted to maintain a fixed direction in azimuth, of a housing for mounting 15 said azimuth maintaining device, a cylindrical card fixed to said azimuth device having vertically extending, equally spaced graduations identified by a plurality of groups of correspondingly arranged characters at the respective bases thereof, a reference card rotatably secured to said housing coaxial with but not touching said azimuth device card and having vertically extending, equally spaced graduations each adapted to align with any of the graduations on said cylindrical 20 card, and means for rotatably adjusting said reference card with respect to said housing, there being a window in said housing of sufficient size to clearly view that arc of reference and azimuth cards required to depict at least one group and 25 one graduation thereover of said recurring groups of characters. 30

3. A pilot director for aircraft comprising, in combination, a device having a series of groups of correspondingly arranged direction indicia, a 35 housing for mounting said device, a reference card rotatably secured to said housing coaxial with and freely movable independent of said device and having a plurality of equally spaced rubber lines thereon equal in number to said groups, and means for rotatably adjusting said reference card with respect to said housing, there being a window in said housing of sufficient size to expose a predetermined number only of said 40 rubber lines and direction indicia. 45

4. A pilot director for aircraft comprising, in combination, a directional gyroscope, a housing for mounting said gyroscope, a card fixed to the vertical ring of said gyroscope having a plurality of groups of correspondingly arranged graduations thereon, a reference card rotatably secured to said housing coaxial with and freely movable independent of said first card and having a plurality of equally spaced rubber lines thereon equal in number to said graduation groups, and means 50 for rotatably adjusting said reference card with respect to said housing, there being a window in said housing of sufficient size for viewing predetermined numbers of groups and rubber lines of 55 said first and said reference cards. 60

5. A pilot director for aircraft comprising, in combination, a directional gyroscope, a housing for mounting said gyroscope, a card fixed to the vertical ring of said gyroscope having a plurality of equally spaced graduations each provided with 65 a numeral such that the whole forms a series of groups of correspondingly arranged numerals, a reference card rotatably secured to said housing coaxial with and freely movable independent of said first card and having equally spaced graduations identical in number to said recurring groups of characters, and means for rotatably adjusting said reference card with respect to said housing, there being a window in said housing of sufficient size to clearly view that arc of said first and ref- 70 75

erence cards required to expose at least one group and one graduation thereover of said recurring groups of graduations.

6. A pilot director for aircraft comprising, in combination, a directional gyroscope, a housing for mounting said gyroscope, a cylindrical card fixed to the vertical ring of said gyroscope having vertically extending equally spaced graduations provided with a series of groups of correspondingly arranged numerals at the respective bases thereof, a reference card rotatably secured to said housing coaxial with and freely movable inde-

pendent of said cylindrical card and having vertically extending equally spaced graduations each adapted to align with any of the graduations on said cylindrical card, and means for rotatably adjusting said reference card with respect to said housing, there being a window in said housing of sufficient size to clearly view that arc of cylindrical and reference cards required to expose at least one group and one graduation thereover of said recurring groups of graduations. 10
